UNITED STATES PATENT OFFICE.

HARVEY COCKELL AND WILLIAM H. FISH, OF COLUMBUS, OHIO.

ROASTING AND SMELTING FURNACE.

SPECIFICATION forming part of Letters Patent No. 772,925, dated October 25, 1904.

Application filed March 27, 1903. Renewed March 28, 1904. Serial No. 200,441. (No model.)

To all whom it may concern:

Be it known that we, HARVEY COCKELL and WILLIAM H. FISH, citizens of the United States, residing at Columbus, in the county 5 of Franklin and State of Ohio, have invented certain new and useful Improvements in Roasting and Smelting Furnaces; and we do hereby declare the following to be a full, clear, and exact description of the invention, such as will 10 enable others skilled in the art to which it appertains to make and use the same.

The object of this invention is to provide an improved ore roasting and smelting apparatus in which the work of extracting the metal is 15 expeditiously and economically effected.

The invention consists in the construction hereinafter described and claimed whereby the pulverized ore or pulp is simultaneously fed and roasted without subjecting the ore 20 directly to the return blasts from the smelting-furnace.

The invention also embraces details of construction whereby the smelting process is expedited and made more nearly perfect.

25 In the accompanying drawings, Figure 1 depicts a sectional view of the several parts of the apparatus. Fig. 2 is a sectional view of the furnace on the plane indicated by the line $\alpha\alpha$, Fig. 1. Fig. 3 is a section on line yy , Fig. 1.

In the views, 1 designates the furnace, which has an inclined trough-like bottom 1^a , with a 30 tap 1^b to discharge the slag and a tap 1^c to discharge the metal. These taps are of course to be plugged during the smelting process.

35 Leading into the top of the furnace and pointing toward the bottom and approximately toward the center thereof or toward each other are fuel and ore inlets 2. Connected with

40 these inlets are pipes 3, having a common stem 3^a , through which air is supplied. Connected with the pipes 3 are oil or gas pipes 4, having suitable valves 4 a for regulating the quantity of oil or gas admitted. Leading out

45 of the top of the furnace is a flue 5, containing an expanded hood or jacket 5^a . In this hood is located an ore feeding and roasting chamber 6, containing a conveyer or screw 7. The chamber 6 is connected with the pipes 3 50 near the inlet-pipe 3^a ; but said chamber has

no communication with the hood 5^a or flue 5. The shaft of the conveyer or screw is shown to have gearing by which it may be driven to feed the pulp or ore through the roasting-chamber 6. The roasting-chamber 6 has communicating with it a hopper 8, through which the ore is supplied thereto, and the hopper is furnished with a valve 8^a , by which the quantity passing into the roaster can be regulated. The hopper also has no communication with the interior of the hood. From this construction it will be observed that the pulp or ore is roasted in the feeding-chamber by the heated gases escaping from the furnace without being impeded by them. The air and oil 60 or gas constitute the fuel, and the ore is thoroughly mixed and subjected to intense heat in the smelting-chamber, which quickly reduces the metallic portions to a fluid state. The metal is drawn off through the lower tap 1^c . 65 The slag can of course be first drawn off through the tap 1^b . The hood 5^a constitutes also a trap to catch the deposit of fumes from the furnace, and as these oftentimes contain some metal the hood is provided with a movable cover 5^b to permit access to the interior of the hood for the purpose of removing the deposit and cleaning the same.

Because the fuel-inlets at the top of the furnace are directed toward the bottom of the 80 furnace and toward each other the heat is intensified.

Additional fuel-burners in the walls of the furnace can be employed to increase the heat, if deemed necessary.

85 The fuel may be supplied to the furnace independently of the air-pipes 3, and the ore may be supplied to the furnace by gravity alone and without the aid of the air-blast.

The forms of the parts can be changed without departing from the gist of the invention.

What we claim, and desire to secure by Letters Patent, is—

1. In an ore roasting and smelting apparatus, a furnace, an outlet for the products of combustion therefrom, an ore feeding and roasting chamber located in said outlet having a separate discharge into said furnace, and a fuel-supply communicating with said discharge.

2. In an ore roasting and smelting apparatus, a furnace, an outlet for the products of combustion therefrom, an ore feeding and roasting chamber located in said outlet having a separate discharge into said furnace and an air-inlet communicating with the last-named discharge.
3. In an ore roasting and smelting apparatus, a furnace, an outlet for the products of combustion therefrom, an ore feeding and roasting chamber located in said outlet hav-

ing a separate discharge into said furnace, an air-inlet communicating with the last-named discharge, and a fuel-supply also communicating with said discharge.

In testimony whereof we affix our signatures in presence of two witnesses.

HARVEY COCKELL.
WILLIAM H. FISH.
